CLAIM

The ornamental design for a portable art case, as shown and described.

DESCRIPTION

FIG. 1 shows a perspective view of the portable art case with the three components in their closed position,
FIG. 2 shows a top view thereof,
FIG. 3 shows a front view thereof.

FIG. 4 shows a perspective view of the portable art case with the lid and drawer each partially open relative to the base,
FIG. 5 shows a top view thereof,
FIG. 6 shows a front view thereof.

FIG. 7 shows a perspective view of the portable art case with the three components fully detached from each other,
FIG. 8 shows a top view thereof; and,
FIG. 9 shows a front view thereof.
